O. M. Bond

ATTORNEY

UNITED STATES PATENT OFFICE.

ROSS LLOYD, OF SCHOMBERG, ONTARIO, CANADA.

WATER-HEATING SYSTEM FOR STOVES.

Application filed September 5, 1922. Serial No. 586,316.

To all whom it may concern:

Be it known that I, Ross Lloyd, a citizen of Dominion of Canada, and resident of Schomberg, in the county of York and Province of Ontario, Dominion of Canada, have invented certain new and useful Improvements in Water-Heating Systems for Stoves, of which the following is a specification.

10 This invention has relation to certain new and useful improvements in a water heating system for a stove and has for its primary object the provision of a system of the character stated which may be adapted to 15 oil stoves or the like to utilize the heating from each burner for heating water circulating through the separate water jackets provided for the various burners.

The invention has for another object the 20 provision of a water heating system for a stove comprising a water tank a distributing pipe and return pipe connected with the water pipe and having communication with opposite ends of water chambers provided in 25 jackets placed above each burner, whereby the heat from the burner may be utilized for heating the water in the system.

The invention has for a further object the provision of a water heating system for 30 a stove such as oil stove or gas stove and which water heating system will be of simple design and composed of the minimum number of parts of simple and inexpensive construction and arranged so as to provide 35 for the highest efficiency of operation of the system.

With the foregoing and other objects in view as will appear as the description proceeds, the invention consists in the novel 40 construction, combination and arrangement of co-operating elements as hereinafter more specifically set forth, claimed and shown in the accompanying drawings forming a part of the present application, in which:

45 Fig. 1 is a perspective view of a conventional form of stove with my invention incorporated therein.

Fig. 2 is a horizontal section substantially on the plane of line 2—2 of Fig. 1, looking 50 in the direction indicated by the arrows and disclosing clearly the construction and arrangement of the parts of the water heating system.

Referring more in detail to the drawings 55 in which similar reference characters designate corresponding parts throughout the

several views, 5 indicates in general an oil stove of conventional form and including a burner 6 with the heat retaining and directing chambers 7 positioned thereon to 60 retain and direct the heat from the burner 6 to the burner plates 8 on the top plate 9 of the stove 5. The heat retaining and directing chambers 7 may be of rectangular form in plan and in elevation, as shown in 65 the drawings or of any other suitable configuration and design.

Secured in a suitable manner on the upper end of each heat retaining member 7 is a substantially square ring shaped water 70 jacket 10. The water jacket 10 has an exterior diameter substantially the same as the interior diameter of the heat retaining and directing chambers 7 so as not to interrupt the passage of the heat from the burner 6 75 to the burner plate 8. This may be readily understood by referring to the drawings especially Fig. 1. Each water jacket 10 has a transverse partition 11 in one side, preferably the rear side and a branch pipe 80 12 connects with the water jacket 10 to one side of the partition 11. This branch pipe 12 extends to the cold water distributing pipe 13 which latter has one end connected with the lower portion of the water supply 85 tank 14 resting on an extended end of the stove top plate 9. A hot water return pipe 15 also has one end connected with the water supply tank 14. The branch pipes 16 90 are carried by the hot water return pipe 15 95 for connection with the water jackets 10 on the other sides of the partitions 11. The free ends of the pipes 13 and 14 are closed by end caps 17 or these pipes may have their ends closed by any other suitable means.

It is believed the complete construction and operation of the water heating system for the stove may now be readily understood from the foregoing paragraphs taken in 100 connection with the accompanying drawings without further detailed description. It may be briefly stated, however, that the water from the water supply tank 14 will pass through the water distributing pipe 13 105 and by way of branches 12 thereof into the water jackets 10. As the water circulates through the water jackets 10 the water will be heated. The heated water will then pass through the branch pipes 16 and into the 110 hot water return pipe 15 by means of which it will be carried back to the tank 14 and re-

- sulting in a heating of the water in the entire system as the burners 16 are in use. The entire water heating system is of simple construction and operation and may be applied 5 to the stove of conventional form now in use without material alteration thereof and without any change in the operation of the stoves. This system provides separate units which can be easily changed when required.
- 10 While the preferred embodiment of the invention has been disclosed, it is to be understood that minor changes in the detail of construction and arrangement of parts may be resorted to within the scope of what is 15 claimed without departing from the spirit of the invention.

What I claim as new is:

1. A water heating system for a stove comprising a water supply tank, a water distributing pipe, a water return pipe, a water jacket adapted to be mounted on a burner of the stove and in the path of the heat produced by said burner, and heat retaining and directing chambers, said water jacket 20 being supported on the upper end of said chambers, said water distributing and water return pipes being connected with said water jacket so as to assure circulation of the water through said water jacket after leaving the water distributing pipe and previously to reaching the water return pipe, said water jacket having a divisional diaphragm at one side the distributing and return pipe of each jacket being connected upon opposite sides of said diaphragm.
2. A water heating system for a stove having a plurality of burners, said water heat-

ing system including a separate water jacket for each burner structure, a heat retaining 40 and directing chamber for each water jacket, each water jacket being mounted upon a heat retaining and directing chamber and having a transverse partition, a water supply tank, a water distributing 45 pipe extending from water supply tank, branch pipes extending from said water distributing pipe to each water jacket on one side of the partition of the latter, a hot water returning pipe connected with said 50 water tank and branch pipes extending from each water jacket on the remaining side of the partition thereof and connecting with the hot water return pipe.

3. A water heating system for a stove comprising a plurality of heat retaining and directing chambers, a plurality of water jackets separate from and adapted to be mounted on the heat retaining and directing chamber for each burner of the stove, each 60 water jacket having a divisional diaphragm at one side, each water jacket having an interior diameter equal to the interior diameter of the heat retaining and directing jackets supporting the same, a water supply 65 tank, a distributing pipe extending from said water supply tank, a return pipe connected with said water supply tank and branch pipes extended from said water distributing pipe and said water return pipe 70 to the said water jackets at opposite sides of said diaphragm.

In testimony whereof, I affix my signature.

ROSS LLOYD.
